SHEET BUNDLE HANDLING APPARATUS

David V. Prentice and Edwin M. Heth, Portland, Oreg., assignors to Prentice Machine Works, Inc., Portland, Oreg., a corporation of Oregon

Filed Nov. 4, 1957, Ser. No. 694,242

11 Claims. (Cl. 214—1)

This invention relates to sheet bundle handling apparatus, and more particularly to apparatus for aligning the edges of a bundle of sheets along one side of the bundle preparatory to further treatment of the sheets.

In the manufacture of a composite board, such as plywood or other laminated board, each layer of veneer in the board is usually made up of a plurality of sheets of veneer which have been joined to one another in longitudinal edge abutting relationship. In order to prepare these veneer sheets for being joined to one another, a stack of sheets is usually passed through a veneer jointer where the edges to be joined are cut along a straight line. This invention has to do with preparing a bundle or stack of sheets for delivery to a jointer and comprises jogger or shaker apparatus and material handling apparatus whereby a stack of veneer sheets may be shaken to align the edges of the sheets along one side of the stack prior to sending the sheets to a jointer for cutting.

A requirement of such apparatus is that the bundle or stack be held relatively loosely during the shaking operation. This enables the various sheets of a stack to move relative to each other during alignment. The sheets are usually held in a vertical position during shaking, gravity functioning to pull the sheets into alignment. After alignment, a bundle is turned over on its side, and the bundle is transported to the usual veneer jointer. In moving from a vertical to generally horizontal position, it is extremely important that no forces be exerted on the sheets which would tend to misalign them, and that the sheets be firmly clamped so as to prevent them from shingling out, or other disarrangement thereof.

Generally this invention features the provision of a number of pairs of opposed confining arms arranged to retain the sheets of a bundle during shaking, the pairs of arms being spaced at intervals transversely of the direction of travel of bundles through the apparatus. The arms of each pair are pivotally mounted relative to the frame of the apparatus. Mechanism is provided for pivoting the free ends of each arm above the support plane or treating bed provided by the frame. In their raised position, a confined treating zone or channel is defined by the arms which extends transversely across the support plane of the apparatus and is adapted to hold loosely a bundle of sheets during shaking of the sheets. A pair of snubber arms are also provided, operable, after the sheets have been shaken, to sweep across the confined treating zone defined by the confining arms and to clamp against a bundle contained therein. The snubber arms maintain a clamping pressure on a bundle during the time that the bundle is being turned over.

Included in the novel apparatus of this invention are a

2

number of pivotal positioning arms, pivoted relative to the frame below the support plane provided by the frame. The snubber arms are pivoted to the nonpivoted ends of the positioning arms. Mechanism interposed between a confining arm and a positioning arm is operable to pivot the positioning arm to a fixed angular position, ordinarily a perpendicular position, relative to the confining arm. Additional mechanism carried by a positioning arm is operable to move a snubber arm pivoted thereon against a bundle thereby to clamp against the same. The snubber, positioning, and clamping arms are movable as a unit when turning over a bundle, and skewing forces which would tend to shingle or misalign a bundle are eliminated.

Each snubber arm is pivotally mounted on an end of a positioning arm preferably a distance ranging from about one-half to about the full distance of the spacing between opposed confining arms when the confining arms occupy an upright position. In this manner, the arc made by the end of the snubber arm in moving into clamping engagement approximates a horizontal sweep. Further, rolls are carried by the snubber arms for producing the clamping contact of the snubber arms. The rolls, in combination with the direction of the sweep of the arms, insure that a bundle is not subjected during compression to skewing forces which would tend to displace the sheets once they have been jogged into an aligned condition.

Other features, novel objects and advantages are attained by the present invention, which will become more fully apparent from reading the following description, the invention being described hereinbelow in conjunction with the accompanying drawings wherein:

Fig. 1 is a top view of a jogger apparatus constructed according to an embodiment of this invention;

Fig. 2 is a side elevation along the line 2—2 in Fig. 1; 35 Fig. 3 is an end view along the line 3—3 in Fig. 2, illustrating one position of the various arm members in the apparatus; and

Figs. 4, 5, and 6 are views similar to Fig. 3, save that the arm members in the apparatus are shown in the different positions which they occupy during operation of the apparatus.

Referring now to the drawings for a more complete description of an embodiment of this invention, and more particularly to Figs. 1 and 2, the apparatus illustrated 45 comprises generally inner and outer frame portions 10 and 11 respectively. Frame portions 10 and 11 constitute the frame structure for the apparatus. Frame portion 10 is comprised of horizontal members 12, 13, and 14 suitably rigidized as by upright members, such as upright member 18 disposed on either side of inner frame portion 10. Each of the outer frame portions 11 is comprised of an upright such as upright 19 affixed in an appropriate manner to the floor.

Moving along the top of the frame structure on supports 50 16 are a series of continuous belts or transport means indicated at 21, 22, 23, and 24. These belts may be driven in any appropriate manner, as by motor and pulley, and are operable to transport bundles of veneer deposited thereon from right to left as viewed in Figs. 3, 4, 5, and 6. The upper surfaces of the belts define a support plane for the treatment of a bundle of sheets deposited thereon.

With reference again to Figs. 1 and 2, extending across the upper ends of upright members 18, on each side of inner frame portion 10, is a stub plate 26. Stub plates

26 mount in parallel alignment a pair of horizontal shafts 27 and 28 extending across the frame transversely of the direction of travel of a stack of veneer deposited on belts 21-24. Shafts 27 and 28 are rotately mounted, as by brackets 29 secured to the upper surfaces of stub plates 26.

Affixed to each of the shafts 27 and 28 for rotation therewith are a series of pairs of confining arm members, indicated at 31, 32, 33, and 34. Each pair of confining arms includes one confining arm spaced forwardly in the frame, (the lower set of arms in Fig. 1) and another confining arm spaced rearwardly in the frame (the upper set of arms in Fig. 1). The arms each have an elongated portion 38 (see Fig. 3) extending outwardly of the shaft mounting the arm, and adapted when raised, as shown in Fig. 5, to offer an elongated rest surface for a stack of veneer sheets held thereinbetween. The confining arms on one side of the apparatus, i.e., arms 34 in the embodiment illustrated, also include a stub portion 39, to which is pivotally connected links 41. The foremost confining arms are aligned with each other on shaft 27, and the rearmost confining arms are aligned with each other on shaft 28. Shafts 27, 28, which constitute the pivot axes for the confining arms, are spaced below the support plane defined by belts 21-24, the arms being movable from a position located below the support plane to the upright position shown in Fig. 5.

The confining arms are simultaneously raised from their lowered positions shown in Fig. 3, to their elevated or raised positions illustrated in Fig. 5, by means of a fluid motor 42. Fluid motor 42 may be a conventional piston-cylinder device, having inlet and exhaust connections 43 (see Fig. 2) connected to a pressure fluid source (not shown). Fluid motor 42 is suitably secured at its base to upright member 18, and the rod 46 for the motor is guided in its vertical reciprocation by means of runner element 47 secured in an appropriate manner to the rod as by elbow 49 which is affixed to rod 46 through a cross member 51 and nuts 52. Runner element 47 reciprocates in a guide element 53, guide element 53 having a pair of shoulders 54 and 56 (see Fig. 5) which extend outwardly and encompass lateral sides of the runner element. The guide element is secured to upright member 18 in any suitable manner.

The lower ends of links 41 are pivotally connected to the outer ends of cross member 51. Since all the confining arms are affixed to either shaft 27 or shaft 28, when fluid motor 42 is expanded to cause upward movement of the rod in the motor, rotation of shafts 27 and 28 in opposed directions occurs, and all the confining arms move from their lay-down or lowered position of Fig. 3 to their raised position of Fig. 5.

Affixed to the inner side of upright member 18, on either side of inner frame portion 10, are a pair of vertically spaced guide elements, such as guide elements 61, 62, shown in Fig. 2. Each resembles in configuration guide element 53. Reciprocating in these guide elements are runner elements 63 and 64, which are affixed to and guide the travel of a joggle platform structure indicated generally at 66.

Specifically, joggle platform 66 includes cross members 67 and 68, affixed to spaced uprights, such as upright 69. Secured to each upright 69 are a number of platform elements 71. These platform elements, in the lowered position which is shown in Fig. 2, are spaced vertically slightly above shafts 27 and 28. The upper surfaces of the platform elements lie in a common horizontal plane, and in their lowered positions, are spaced at or slightly below the level of the support plane defined by belts 21-24. The platform elements are moved up and down by vertical reciprocation of joggle platform structure 66, and function to shake a bundle of veneer sheets deposited thereon whereby the lower edges of the sheets in the bundle move into alignment.

The joggle platform structure may be reciprocated in any suitable manner. Referring to Fig. 2, extending between horizontal member 12 and the lower end of upright 69 is an expandible fluid motor 76, having inlet and exhaust connections 77. A similar motor is connected to the platform structure at the other side of the machine. Platform structure 66 is moved up and down within guide elements 61 and 62 at each end of the machine by admitting pressure fluid recurrently first to the lower and then to the upper of the connections 77 for each motor. The motors expand and contract in unison, both ends of the platform structure moving in the same direction at any given time.

Referring again to Figs. 1 and 2 rotatably mounted on shaft 28 next to each of the confining arms carried by the shaft in a positioning arm member. These positioning arm members are indicated at 81, 82, 83, and 84. As can best be seen in Figs. 3-6, the positioning arms pivot about shaft 28, from a lowered position wherein the arms lie beneath the support plane of the belts, to the raised vertical position shown in Figs. 4 and 6. The positioning arm members rotate about shaft 28, so that pivotal movement of the positioning arms occurs about the pivot axis for the confining arms. The outermost positioning arms 81 and 84 are provided with an extension, indicated for arm 84 at 86.

Interposed between an ear portion 87 of each of the positioning arms, and the confining arm mounted adjacent the positioning arm, is a fluid motor 91. The motor is pivotally connected to the confining arm and positioning arm. Expansion of fluid motor 91 causes the positioning arm to swing from an aligned position relative to the confining arm associated therewith, as shown in Fig. 3, to a position perpendicular or normal to the confining arm, as shown in Figs. 4, 5, and 6. The stroke of each fluid motor determines the perpendicular position of the confining arm.

Pivottally connected to the extension 86 of each of the outermost positioning arms, at a point spaced from shaft 28 a distance equal to slightly more than one-half the distance between opposed confining arms when they occupy a vertical position (see Fig. 5), is a snubber arm 96. Each snubber arm is slightly crooked in shape, and has pivotally connected to the elbow portion of the arm another fluid motor 97. The other end of fluid motor 97 is pivotally connected to extension 86 of the positioning arm which mounts the snubber arm. Extension of fluid motor 97 results in the snubber arm pivoting in a clockwise direction in Figs. 3, 4, 5, and 6.

Each snubber arm 96 curves inwardly slightly, and then curves outwardly from its elbow. The inner bend of each arm mounts a roller 98. Another roller 99 is mounted at the outer end of each snubber arm. These rollers are included so that the clamping contact between each snubber arm and a bundle of sheets is a rolling one, instead of a sliding type contact which would tend to skew or shingle the sheets in a stack. The snubber arm, positioning arm mounting the snubber arm, and the confining arm adjacent this positioning arm, together with the expandible motors moving the various arms, move as a unit with pivotal movement of the confining arm.

The operation of the hereinabove described apparatus is as follows:

A stack of veneer sheets, such as stack 101 in Fig. 4, is deposited on belts 21 to 24, the belts moving the stack from right to left in Fig. 4. Fluid motors 91 are then actuated to extend the motors, causing the positioning arms to move to a perpendicular position relative to the confining arms. If the confining arms are horizontal, actuation of motors 91 functions to move the positioning arms to a vertical position. Travel of the stack to the left in Fig. 4 is limited by movement of the stack against the upright positioning arms. When this occurs, the belts are stopped, and the stack is ready to be moved into position for a shake.

Prior to shaking a stack of sheets, fluid motor 42 is actuated, which operates through links 41 to move opposed confining arms of each pair of confining arms to a vertical position, illustrated in Fig. 5. The confining arm members in this position define a treating zone or channel extending transversely across the machine. The width of a stack of sheets is selected so that the sheets will not be tightly compressed by movement of the confining arms upwardly to the position shown in Fig. 5. The snubber arms are moved to a horizontal position, as shown in dotted lines in Fig. 5, when motor 42 is actuated.

Motors 76 of the shaker platform structure are then actuated, causing the platform structure to move up and down. This results in the edges of the sheets in the stack aligning themselves within the confines of the confining arms.

After alignment of the sheet edges, extension of fluid motors 97 causes snubber arms 96 to sweep across the treating channel or zone defined by the confining arms, from the position shown in dotted lines in Fig. 5 to the position shown in full lines in Fig. 5. The locations of the pivot connections for the snubber arms enable the clamping portions of the snubber arms to move while clamping onto a stack in substantially horizontal sweeps. The sheets are contacted by rollers 98 and/or 99, depending upon the height of the sheets and the width of the stack treated.

Contraction of fluid motor 42 connected to the confining arms through links 41 operates to swing the confining arms to the position illustrated in Fig. 6, the positioning arms and the snubber arms moving in unison with the confining arms and at the same time maintaining the stack of sheets tightly compressed. By maintaining the clamping pressure, shingling or falling out of the sheets as the stack is turned on its side is effectively prevented.

When the stack of sheets has been turned to the horizontal position illustrated in Fig. 6, the positioning arms are returned to the horizontal position illustrated in Fig. 3 by contraction of fluid motors 91. Further, the snubber arms are moved to a horizontal position by contraction of fluid motors 97.

It will be noted that the confining arms are driven by a single motor, the confining arms being affixed to shafts 27, 28. Movement of all of the confining arms thus occurs simultaneously. This prevents the possibility of one of the confining arms moving at a slightly faster rate than another of the confining arms when the bundle is laid down, which could result in twisting of the stack and misaligning of edges.

While there has been described only a single embodiment of this invention, it should be obvious that variations in the organization and parts employed are possible without departing from the spirit of this invention, and it is intended to cover all variations and modifications which would be apparent to one skilled in the art and that come within the scope of the appended claims.

It is claimed and desired to secure by Letters Patent:

1. In sheet bundle handling apparatus, said apparatus comprising a frame, support means defining a support plane for the treatment of a bundle of sheets thereon, a confining arm member pivotally mounted on said frame beneath said support plane and having a non-pivoted end movable above the plane of the table, means for raising the nonpivoted end of said confining arm member above said support plane, and means spaced from and cooperating with said confining arm member to define with said confining arm member when raised a confined treating zone for treating a bundle of sheets, the improvement comprising a positioning arm member pivotally mounted on said frame beneath said table and having a nonpivoted end movable above the plane of the table, means for swinging said positioning arm

member to a fixed angular position relative to said confining arm member and maintaining the same in said position during pivotal movement of the confining arm member, a snubber arm member pivotally mounted to the nonpivoted end of said positioning arm member, and means interposed between the positioning arm member and snubber arm member and movable with the positioning arm member for pivoting said snubber arm member toward said confining arm member whereby tamping pressure may be produced between said confining arm member and said snubbing arm member.

2. Sheet bundle handling apparatus comprising a frame and support means defining a support plane for the treatment of a bundle of sheets thereon, a pair of opposed confining arm members pivotally mounted on said frame beneath said support plane, means for raising the free ends of said confining arm members above said support plane, said confining arm members when raised defining a confined treating zone for treating a bundle of sheets, a positioning arm member pivotally mounted on said frame beneath said table, a snubber arm member pivotally mounted to a nonpivoted end of said positioning arm member, means interposed between one of said confining arm members and said positioning arm member and movable with said one confining arm member for pivoting said positioning arm member to a fixed angular position relative to said one confining arm member, and means interposed between said positioning arm member and said snubber arm member and movable with said positioning arm member for pivoting said snubber arm member toward said one confining arm member, said snubber arm member and said one confining arm member operating to clamp onto treated bundles when said one confining arm member is lowered toward said support plane.

3. Sheet bundle handling apparatus comprising a frame and support means defining a support plane for the treatment of a bundle of sheets thereon, a confining arm member pivotally mounted on said frame beneath said support plane, means for raising a free end of said confining arm member above said support plane, means spaced from and cooperating with said confining arm member to define with said confining arm member when raised a confined treating zone for treating a bundle of sheets, a positioning arm member pivotally mounted on said frame beneath said table, a snubber arm member pivotally mounted to a nonpivoted end of said positioning arm member, means interposed between said confining arm member and said positioning arm member and movable with said confining arm member for pivoting said positioning arm member to a fixed angular position relative to said confining arm member, and means interposed between said positioning arm member and said snubber arm member and movable with said positioning arm member for pivoting said snubber arm member toward said confining arm member, said snubber arm member and said confining arm member operating to clamp onto treated bundles when said confining arm member is lowered toward said support plane.

4. Jogger apparatus for aligning the edges of a bundle of sheets comprising a frame and support means defining a support plane for the treatment of a bundle of sheets thereon, a confining arm member mounted on said frame for pivotal movement about a pivot axis spaced below said support plane, means for raising a free end of said confining arm member above said support plane, means spaced from and cooperating with said confining arm member to define with said confining arm member when raised a confined treating zone for treating a bundle of sheets, jogger platform means having a platform surface mounted in said frame at the base of said treating zone, a positioning arm member mounted on said frame for pivotal movement about the pivot axis for said confining arm member, said positioning

arm member in a lowered position being spaced below the platform surface of said jogger platform means, a snubber arm member pivotally mounted to a nonpivoted end of said positioning arm member with the free end thereof adapted to sweep through said treating zone above said jogger platform means, means interposed between said confining arm member and said positioning arm member and movable with said confining arm member for pivoting said positioning arm member to a fixed angular position relative to said confining arm member, and means interposed between said positioning arm member and said snubber arm member and movable with said positioning arm member for pivoting said snubber arm member toward said confining arm member, said snubber arm member and said confining arm member operating to clamp onto treated bundles when said confining arm member is lowered toward said support plane.

5. Jogger apparatus for aligning the edges of a bundle of sheets comprising a frame and support means defining a support plane for the treatment of a bundle of sheets thereon, a pair of confining arm members pivotally mounted on said frame, each of said confining arm members pivoting about a pivot axis spaced below said support plane, means for raising free ends of said confining arm members above said support plane, said confining arm members when raised defining a confined treating zone for treating a bundle of sheets, jogger platform means having a platform surface mounted in said frame at the base of said treating zone, a positioning arm member mounted on said frame for pivotal movement about the pivot axis for one of said confining arms, said positioning arm member in a lowered position being spaced below the platform surface of said jogger platform means, a snubber arm member pivotally mounted to a nonpivoted end of said positioning arm member with the free end thereof adapted to sweep through said treating zone above said jogger platform means, means interposed between said one confining arm member and said positioning arm member and movable with said one confining arm member for pivoting said positioning arm member to a fixed angular position relative to said one confining arm member, and means interposed between said positioning arm member and said snubber arm member and movable with said positioning arm member for pivoting said snubber arm member toward said one confining arm member, said snubber arm member and said one confining arm member operating to clamp onto treated bundles when said one confining arm member is lowered toward said support plane.

6. Jogger apparatus for aligning the edges of a bundle of sheets comprising a frame, transport means carried by said frame for transporting bundles of sheets in a path along said frame, said frame and transport means defining a support plane for the treatment of a bundle of sheets, plural pairs of confining arm members spaced on said frame transversely of the movement of sheets on said frame, said confining arm members pivoting on said frame, means for raising the free ends of said confining arm members above said support plane, said confining arm members when raised defining a confined transverse treating channel for the treatment of bundles of sheets, at least two of said pairs of confining arm members having a positioning arm member associated therewith, one for each pair of confining arm members, each of said positioning arm members being mounted for pivotal movement related to its associated confining arm member, a snubber arm member pivotally mounted to the nonpivoted end of each of said positioning arm members, a first motor means extending between each of the positioning arm members and the confining arm member associated therewith, and a second motor means extending between each of the snub-

ber arm members and the positioning arm member mounting the snubber arm member, said snubber arm members clamping onto treated bundles and moving with the bundles when said confining arm members are lowered toward said support plane.

7. Jogger apparatus for aligning the edges of a bundle of sheets comprising a frame, transport means carried by said frame for transporting bundles of sheets in a path along said frame, said frame and transport means defining a support plane for the treatment of a bundle of sheets, plural pairs of confining arm members spaced on said frame transversely of the movement of sheets on said frame, said confining arm members pivoting on said frame about a pivot axis spaced below said support plane, means for raising the free ends of said confining arm members above said support plane, said confining arm members when raised defining a confined transverse treating channel for the treatment of bundles of sheets, jogger platform means having a platform surface mounted in said frame at the base of said treating channel, at least two of said pairs of confining arm members having a positioning arm member associated therewith, one for each pair of confining arm members, each of said positioning arm members being mounted for pivotal movement about the pivot axis of its associated confining arm member, each positioning arm member in a lowered position being spaced below the support surface of said jogger platform means, a snubber arm member pivotally mounted to the nonpivoted end of each of said positioning arm members, the free ends of said snubber arm members being adapted to sweep through said treating channel above said jogger platform means, means interposed between each positioning arm member and the confining arm member associated therewith for pivoting the positioning arm member to a fixed angular position relative to its confining arm member, and means interposed between each positioning arm member and the snubber arm member mounted thereon for pivoting the free end of the snubber arm member toward a confining arm member, said snubber arm members operating to clamp onto treated bundles.

8. Jogger apparatus for aligning the edges of a bundle of veneer sheets comprising a frame, a pair of parallel shafts rotatably mounted in said frame and extending across said frame, at least two pairs of opposed confining arm members secured to said shafts, one confining arm member of each pair being secured to one of said shafts and the other confining arm member of each pair being secured to the other of said shafts, a positioning arm member associated with each of the confining arm members secured to said one shaft rotatably mounted on said one shaft, a snubber arm member pivoted on a free end of each of said positioning arm members, means for rotating said shafts simultaneously in opposed directions, means interposed between each of the confining arm members which is associated with a positioning arm member and the positioning arm member for pivoting the positioning arm member, and means interposed between each positioning arm member and the snubber arm member pivoted thereon for pivoting the snubber arm member.

9. The apparatus of claim 8 wherein the snubber arm members each have a roll rotatably carried thereon, said roll providing the clamping contact for the snubber arm member.

10. The apparatus of claim 8 wherein the snubber arm members are pivoted about pivot axes spaced on the positioning arm members from said one shaft which mounts the positioning arm members a distance ranging from about one-half to about the full distance existing between the confining arm members when they occupy an upright position.

11. Veneer sheet jogger apparatus for aligning the edges of a bundle of sheets comprising a frame, means for conveying bundles of sheets along said frame, a shaft rotatably carried in said frame extending transverse-

ly of the direction of travel of sheets along the frame, at least two confining arm members secured to said shaft, said confining arm members being spaced on said shaft and aligned with each other so as to provide together support for a bundle of sheet, a positioning arm member associated with each of said confining arm members rotatably mounted on said shaft, a snubber arm member pivoted on a free end of each of said positioning arm members, means for rotating said shaft, means interposed between each confining arm member and each positioning arm member which is associated therewith for rotating the

5 positioning arm member, and means interposed between each positioning arm member and the snubber arm member pivoted thereon for pivoting the snubber arm member.
